Specification of Letters Patent.

Patented Aug. 8, 1911.

Application filed May 25, 1907. Serial No. 375,615.

To all whom it may concern:

Be it known that I, FRANK S. INGOLDSBY, a citizen of the United States, residing at St. Louis, State of Missouri, have invented 5 a certain new and useful Improvement in Cars, of which the following is a full, clear, and exact description, reference being had to the accompanying drawings.

One of the objects of this invention is to 10 provide a very efficient floor frame for cars.

The invention is well adapted for level floor dump cars, and especially such cars of the Ingoldsby type, wherein there is a central longitudinal supporting structure to 15

which are hinged the doors, which extend outwardly to the car sides.

The present invention is concerned particularly with the longitudinal center member, which in the preferred form is composed of a pair of rolled shapes surmounted by an inverted U-shaped structure held thereto on bridges arranged at points corresponding to the struts and ties of a truss. By this means I am enabled to obtain at 25 once a very stiff and light member. The member is also very strong, the parts being arranged with reference to the strain which comes upon them so that the various rivets are in shear.

30 My invention, furthermore, provides cross-shaped members forming a portion of both the longitudinal member and the cross members to the car sides; these cross-shaped members having their longitudinal arms in compression, and their cross arms with extensions thereof, acting as lateral braces and load supporting beams between the center member and the sides.

The top of the longitudinal member, as 40 well as of the cross members, being rounded, they provide shedding surfaces discharging into openings between them, when the doors, which normally occupy such openings, are dropped.

45 The invention is hereinafter more fully explained and is illustrated in the accompanying drawings.

In the drawings Figure 1 is a plan of a 50 level bottom dump car embodying my invention. Fig. 2 is a side elevation on an enlarged scale of a portion of the longitu-

dinal center member, being a vertical section on the line 2—2 of Fig. 1. Figs. 3 and 4 are cross sections, as indicated by the correspondingly numbered lines in Fig. 1. 55 Fig. 5 is a sectional plan of the longitudinal center member, the section being taken a short distance below the crown. Fig. 6 is a perspective view of the shedding cross at the junctions of the longitudinal and cross members, showing also the channel beneath the cross arms. Fig. 7 is a detail in cross section illustrating a modified means for carrying the hinge pintle for the dumping doors. 60 65

Referring to the parts by reference numerals, 10 represents the sides of the car, which may be plate girders; 11 the longitudinal arms of the cross shaped members in the top of the longitudinal center member; 12 the lateral arms of such crosses; 13 the transverse crowns which continue the cross arms to the car sides, and 14 the dumping doors which are hinged by floor beams 70 75 to the center member and extend outwardly to the car sides.

The longitudinal center member comprises, as shown, a pair of channel beams 20 (arranged with their webs vertical, and their flanges outward) a bottom plate 21 80 riveted to the lower flanges of the channel beams, a pair of vertical plates 22 extending parallel with the channels and above them and nearer together (these plates 22 being connected together at their upper ends 85 by a curved crown) and suitable bridges, to be hereinafter described, supporting the vertical plates from the channels 20. The curved crown connecting the plates 22 is composed of the longitudinal arms 11 of the 90 crosses and suitable filling blocks 25 between the longitudinal arms of successive crosses. These crosses are shown in Fig. 6, and the filling blocks are shaped similarly to the longitudinal arms of the cross. The longi- 95 tudinal arms and the filling blocks each have a curved upper surface and depending vertical flanges 26 to which the plates 22 are riveted.

The floor beams of the dumping doors 100 pass through openings 30 in the plates 22 and are pivoted by hinge pintles 31 at the

center of the car to suitable supporting members, which may be vertical plates flanged and riveted to the plates 22, as shown at 32 in Figs. 3, 4, and 5, or they 5 may be webs depending from the crowns of the cross 11, or filling blocks 25, as shown at 34 in Fig. 7. The dumping doors carry shield plates 40 near their inner edges, and the hinge pintle being located at the center 10 of curvature of the crowns 11 and 25, this shield plate makes close connection with such crowns, thus providing substantially a level bottom when the doors are closed, and making a slope tangent to the curve of the 15 crown when the doors are dropped, thus greatly facilitating the discharge of the load, and preventing lodgment of material, as illustrated in the right hand half of Fig. 3.

20 I have stated that the plates 22 are supported by bridges secured to the channel beams 20. The structure of these bridges varies with the strains to which the various parts of the center member are subjected, the 25 connections being such as to form posts or struts at points where compression would take place and ties at tension points, so that the whole structure makes a truss, parts of the plates 22 and parts of the channels 20 30 acting as struts, ties and counters. By this means the structure may be very materially lightened without interfering with its strength or stiffness.

Fig. 2 shows the truss arrangement, the 35 space between adjacent cross beams being shown as divided into three panels. Accordingly at points beneath the junction of the longitudinal and cross beams, and at two intermediate points the structure should 40 have the character of a strut. At these points I provide bridges consisting of angle bars 50 having a horizontal portion extending across and riveted to the top flanges of the channels 20, as shown at 51; while the 45 vertical portions of these angle bars are bent inward near their ends to lie along the inner face of the webs of the channels, being there riveted, as indicated at 52. Suitable angle pieces 53 lie against the outer face of 50 the plates 22 and the upper surface of the bridge 50 and are riveted to such parts. This makes a very secure post. The downward strains act in shear on the horizontal rivets, this downward strain being also provided for by the extension of the bridge 55 across the top of the channels 20, as explained.

At points midway of the bridges 50, the 60 structure should have the character of a tie or counter, as the strain at these points is tension. The plates 22 and the webs of the channels 20 make good tension members, and to prevent these members pulling apart under such strain, I arrange the bridges at

these points to act as ties. In this case, the 65 bridge 60 comprises a channel with its web horizontal and its flanges facing downwardly, this channel lying between the two channel beams 20. The web of this channel bridge near its ends is turned downwardly 70 and abuts the inner face of the channel beams, being there riveted by horizontal rivets, as indicated at 61.

62 designates vertical angle bars riveted to the plates 22 and to the webs of the channel bridge 60, the outer faces of which these angle bars engage. The outer flanges of these angles are also bent parallel with the channel beams 20 and riveted to their webs as shown at 65. In this instance, the rivets 80 connecting the angle bars 62 with the plates 22, the channel bridge and the beams 20, and the rivets connecting the channel bridge with the beams 20, are all in shear for the tension strain coming at this point.

85 Downward bending of the longitudinal member would tend to cause the upper portion to shift lengthwise on the lower portion. This is effectively resisted by the various rivets in shear of both the strut bridges and 90 the tie bridges.

95 The plates 22 and the webs of the channels 20 together with my bridges 60 act as ties or counters for my center member truss. The truss action is indicated by the broken lines designated "Strut", "Tie" or "Counter" in Fig. 2.

100 The openings 30 in the plates 22, through which the floor beams project and swing, are so arranged as not to interfere with the line of direction of the ties or counters. Moreover, any weakening of the plate 22 by such opening is compensated for by the bracing which comes from riveting the cross plates 32 thereto, and by the flange of the 105 corresponding angle bars 62. This is illustrated in Fig. 2.

110 It will be seen that my trussed center member provides for the various strains of compression, tension and bending to which such member may be subjected, and, as stated, enables this member to be made very light and at the same time very efficient in stiffness and strength. The particular 115 shape of the member is also efficient in providing the central crowned floor member with which the dumping doors co-operate. To enable the hinge pintle of these doors to be conveniently placed or removed, I make horizontal elongations in the floor beam 120 openings, as shown at 33 in Fig. 2. This elongation coming between the ties or counters as well as between the struts of the truss, does not materially weaken the plate, in its 125 action as a strut, tie or counter.

In my car the longitudinal center member is designed to support the load which is above it and half of the load on the doors

of each side thereof, while each car side is designed to support the load on half of the doors held thereby. The cross members between the sides and the center member are therefore simply beams to support whatever material may be carried by them, and to act as lateral bracing for the car floor frame. These beams consist of the transverse arms 12 of the crosses, the shedding crowns 13 and the underlying channel 70. This channel lies with its web horizontal and extends from the car side well toward the center, the web being riveted through the transverse arm 12 of the cross. The shedding crown 13 rests at its inner end on a reduced extension 71 of the arm 12 and its outer end on a block 72, the crown abutting against the tie member 73 which makes a lower chord for the girder side.

To provide end guards for the doors and also to securely heel the vertical posts 75 of the plate girder, I arrange these posts, which are preferably angle bars, in pairs with their projecting flanges adjacent and located slightly outside of the plane of the flanges of the channel 70. I extend these posts below the car side, and between the posts and the channel flanges, I place vertical plates 77 which constitute the end guards. These plates are riveted to the channel flanges, as shown at 78, and to the side posts 75, one of the rivets, as 79, passing through a side post, the plate and flange of the channel. I mount a suitable block 80 on the upper face of the projecting end of the channel 70 and between the vertical posts, this block being riveted to the posts, the channel and car side, as shown in Fig. 4. The end guards may be stiffened by suitable reinforcing members riveted thereto, as the angle bars 81. This arrangement of parts not only operates to provide a very stiff end guard, but also securely heels the lower end of the vertical posts 75, making them effective cantilevers to resist outward bulging.

Having thus described my invention, I claim:

1. In a car, the combination of a member comprising a lower structure, and a surmounting structure secured thereto on bridges, said bridges being arranged at some points to act as parts of struts and at others as parts of ties.
2. In a car, the combination of a center member comprising a lower structure, and a surmounting structure secured thereto on bridges, said bridges being arranged to act alternately as struts and ties with rivets in shear for the corresponding strain.
3. In a car, a supporting structure comprising two longitudinal members, bridges carried thereby, and a narrow upper member, comprising two longitudinal members

extending the length of the car carried by 65 said bridges.

4. In a dump car, a supporting structure comprising two longitudinal members, bridges carried thereby, a narrow upper member carried by said bridges, and dumping doors carried by said upper member. 70

5. In a dump car, the combination of a member comprising a pair of longitudinal beams, bridges carried thereby, a pair of vertical plates carried by the bridges, and a shedding crown carried by the vertical plates. 75

6. In a dump car, the combination of a member comprising a pair of longitudinal beams, bridges carried thereby, a pair of vertical plates carried by the bridges, a shedding crown carried by the vertical plates, and dumping doors supported by the vertical plates and coöoperating with said shedding crown. 80

7. In a car, the combination of a supporting structure comprising lower longitudinal members, and a surmounting member in the form of an inverted U, which does not extend above the level of the floor. 90

8. In a car, the combination of a supporting structure comprising lower longitudinal members, bridges carried thereby, and a surmounting member in the form of an inverted U carried by the bridges. 95

9. In a car, the combination of a central longitudinal member having a lower portion composed of channels with vertical webs, bridges secured to said channels and a superstructure whose cross section is an inverted U carried by said bridges. 100

10. In a car, the combination of a central longitudinal member having a lower portion composed of channels facing outwardly bridges secured to said channels some to the top flange and others to the inner face, and a superstructure whose cross section is an inverted U carried by said bridges. 105

11. In a car, the combination of a longitudinal center structure comprising lower longitudinal members and a longitudinal superstructure carried on bridges by the lower members, some of said bridges secured to the flanges and some to the inner faces of the lower member. 110

12. In a car, the combination of a longitudinal center structure comprising lower longitudinal members and a longitudinal superstructure carried on bridges by the lower members, said superstructure being of a cross section which is substantially an inverted U, and dumping doors carried by the superstructure. 120

13. In a car, the combination of a longitudinal center structure comprising lower longitudinal members and a longitudinal superstructure carried on bridges by the lower members, said superstructure com- 125

prising a pair of vertical longitudinal plates and a curved shedding crown secured thereto.

14. In a car, the combination of longitudinal lower members and a longitudinal superstructure carried thereby and comprising a pair of vertical longitudinal plates and a curved shedding crown secured thereto.

15. In a car, the combination of a structure comprising lower members and a superstructure carried thereby, said superstructure comprising a pair of vertical longitudinal plates and a curved shedding crown secured thereto, the crown member having 10 depending flanges to which said plates are riveted near their upper edges.

16. In a car, the combination of a structure comprising a pair of parallel lower members, bridges extending across said 20 members, and a superstructure carried by the bridges, the bridges being alternately arranged for compression and tension.

17. In a dump car, the combination of a structure comprising a pair of parallel lower members, bridges extending across said members, and a superstructure carried by the bridges, the bridges being alternate members resting on the upper surface of the longitudinal lower member and members 30 abutting and secured to the inner surface of such members.

18. In a car, the combination of a structure comprising a pair of channel beams with their webs vertical, bridges resting on 35 the upper flanges of the channel beams and a superstructure carried by said bridges, forming a composite structure arranged at certain points to act as struts and at others as ties and counters.

40 19. In a car, the combination of a structure including a pair of channel beams with their webs vertical, bridges comprising cross channels with their flanges vertical and the web near its ends bent down vertically and 45 engaging and riveted to the inner face of the channel beams, and a superstructure supported by said bridges.

20. The combination in a dump car, of a central longitudinal member comprising a 50 pair of lower beams, bridges carried thereby, a superstructure carried by the bridges, said superstructure having a cross section like an inverted U, dumping doors having floor beams projecting into the interior of said U, and means for supporting the hinge pintle 55 of the doors.

21. In a dump car, the combination of a longitudinal member having a lower longitudinal portion and an upper portion made 60 narrower and in the form of an inverted U, means in the interior of said U for carrying a hinge pintle, and dumping doors hinged by such pintle.

22. In a dump car, the combination of a

center member whose upper portion is of an inverted U shape, and dumping doors hinged at substantially the center of curvature of the crown of said center member.

23. In a dump car, the combination of a center member having a pair of vertical plates, a crown secured thereto, dumping doors having floor beams extending through openings in the plates and pivoted at substantially the center of the car beneath said crown.

75 24. The combination, in a dump car, of a center member having its upper portion in substantially the form of an inverted U, cross members in substantially the same plane with the crown of the center member, and dumping doors hinged beneath the crown of the center member and between the side portions of such U.

25. The combination, in a dump car, of a center member having its upper portion in substantially the form of an inverted U, cross members in substantially the same plane with the crown of the center member, dumping doors hinged beneath the crown of the center member and between the side portions of such U, and door end guards depending from the cross members.

90 26. The combination, in a dump car, of a center member having its upper portion in substantially the form of an inverted U, cross members in substantially the same plane with the crown of the center member, dumping doors hinged beneath the crown of the center member and between the side portions of such U, channels with their 100 flanges vertical lying along and forming the under portion of the cross members, door end guards riveted to the flanges of the channels, and side posts riveted to the car sides and to the door end guards.

105 27. In a dump car, the combination of a central longitudinal member and car sides, dumping doors pivoted to the central longitudinal member and adapted to be supported at their outer ends by the car sides, 110 the sides and the center member carrying their natural portion of the load, cross beams between the center member and car side having their tops on the same level with the top of the longitudinal member, 115 said cross beams carrying their own load and acting as lateral stiffeners between the center member and car sides, and posts on the outer side of the car side, each cross beam extending between a pair of posts.

120 28. In a dump car, the combination of a central longitudinal member and car sides, dumping doors pivoted to the central longitudinal member and adapted to be supported at their outer ends by the car sides, 125 the sides and the center member carrying their natural portion of the load, cross beams between the center member and car

- side having their tops on the same level with the top of the longitudinal member, said cross beams carrying their own load and acting as lateral stiffeners between the center member and car sides, posts on the outer side of the car sides extending below such sides, and transverse plates for heeling the lower ends of the posts secured to such lower ends and to the cross members.
29. In a car, the combination of a center member comprising a lower structure, and a surmounting structure secured thereto on isolated bridges, said bridges being arranged at some points to act as struts and others as ties, and having rivets in shear for the strain which comes on them.
30. In a dump car, the combination of a member whose upper portion is in the form of an inverted **U**, and dumping doors carried thereby and coöperating with the curved surface of said **U**.
31. In a car, a central longitudinal member whose upper portion is in the form of an inverted **U**, which does not extend above the level of the floor.
32. In a car, a longitudinal center beam composed of members arranged at certain points to act as struts and at others as ties and counters to provide an effective truss, a surmounting member in the form of an inverted **U** forming a shedding member, cross members having shedding surfaces and dumping doors engaging the shedding surfaces of the surmounting member and forming a substantially flat door.
33. In a car, the combination of a supporting structure comprising lower longitudinal members, a surmounting member in the form of an inverted **U**, and a dumping door hinged to the surmounting structure.
34. In a car, the combination of a supporting structure comprising lower longitudinal members, bridges carried thereby, a surmounting member in the form of an inverted **U** carried by the bridges, and a dumping door hinged to the surmounting structure.
35. In a car, the combination of a central longitudinal member having a lower portion composed of channels with vertical webs, bridges secured to said channels, a superstructure whose cross section is an inverted **U** carried by said bridges, and a dumping door carried by said superstructure.
36. In a car, the combination of a longitudinal center structure comprising lower longitudinal members, a hollow longitudinal superstructure carried on bridges by the lower members, and a dumping door carried by said superstructure on a hinge within it.
37. In a car, the combination of a longitudinal center structure comprising lower longitudinal members, a longitudinal superstructure carried on bridges by the lower

members, said superstructure comprising a pair of vertical longitudinal plates and a curved shedding crown secured thereto, and a dumping door carried by said superstructure.

38. In a car, the combination of longitudinal lower members, a longitudinal superstructure carried thereby and comprising a pair of vertical longitudinal plates and a curved shedding crown secured thereto, and a dumping door carried by said superstructure.

39. In a car, the combination of a structure comprising a pair of channel beams with their webs vertical, bridges resting on the upper flanges of the channel beams and having depending flanges between and secured to the channel beams, a superstructure carried by said bridges, and a dumping door carried by said superstructure.

40. In a dump car, a beam in the form of an inverted **U** and a door outside of the **U** and hinged within it.

41. In a dump car, a supporting member of inverted **U** form, a dumping door coöperating with the curve of the **U**, and a floor beam for the door extending within the **U** and there pivoted.

42. In a car, a supporting structure having a pair of walls and a pair of dumping doors on opposite sides thereof, said doors having members extending through said walls respectively.

43. In a car, the combination of a supporting structure having a pair of walls and a pair of dumping doors on opposite sides thereof and hinged between said walls.

44. In a car, the combination of a supporting structure and dumping doors on opposite sides of said structure and hinged within the structure.

45. The combination of a supporting structure having a pair of walls, dumping doors having floor beams extending through openings in the walls and hinged to the structure on coincident axes between the walls.

46. In a dumping car, the combination of a hollow central longitudinal member, doors on opposite sides of said member hinged at the center of the car within the member.

47. In a dumping car, the combination of a central longitudinal member having a pair of walls, doors having floor beams hinged between said walls on axes parallel with the longitudinal center of the car.

48. The combination of a hollow supporting structure and a dumping door outside of said structure and pivotally supported by a member extending within the structure.

49. The combination in a dump car of a hollow supporting structure, a dumping door and a floor beam for the door extending into the interior of such structure and there hinged,

50. In a dump car, the combination of a hollow supporting structure, a dumping door outside of said structure and pivotally supported by a member extending within 5 the structure, said door having a load supporting surface adapted to coöperate with the top of said structure.

51. In a dump car, the combination of a hollow stationary member having a rounded

top, a dumping door coöperating with such 10 top, and a floor beam for the door extending into the hollow structure and there hinged.

In testimony whereof, I hereunto affix my signature in the presence of two witnesses.

FRANK S. INGOLDSBY.
